CLAIM

The ornamental design for a table, as shown and described.

DESCRIPTION

FIG. 1 is a perspective view of a first embodiment of a table showing our design;
FIG. 2 is a top plan view thereof;
FIG. 3 is a front elevation view thereof, the rear being a mirror image;
FIG. 4 is a right side elevation view thereof, the left side being a mirror image;
FIG. 5 is an enlarged fragment of a portion of the table shown in FIG. 1 and labeled 5;
FIG. 6 is an enlarged fragment of a portion of the table shown in FIG. 1 and labeled 6;

FIG. 7 is an enlarged fragment of a portion of the table shown in FIG. 1 and labeled 7;

FIG. 8 is a perspective view of a second embodiment of a table showing our new design;

FIG. 9 is a top plan view thereof;

FIG. 10 is a front elevation view thereof, the rear being a mirror image;

FIG. 11 is a right side elevation view thereof, the left side being a mirror image;

FIG. 12 is an enlarged fragment of a portion of the table shown in FIG. 8 and labeled 12;

FIG. 13 is an enlarged fragment of a portion of the table shown in FIG. 8 and labeled 13;

FIG. 14 is an enlarged fragment of a portion of the table shown in FIG. 8 and labeled 14;

FIG. 15 is a perspective view of a third embodiment of a table showing our new design;

FIG. 16 is a top plan view thereof;

FIG. 17 is a front elevation view thereof, the rear being a mirror image;

FIG. 18 is a right side elevation view thereof, the left side being a mirror image;

FIG. 19 is an enlarged fragment of a portion of the table shown in FIG. 15 and labeled 19;

FIG. 20 is an enlarged fragment of a portion of the table shown in FIG. 15 and labeled 20; and,

FIG. 21 is an enlarged fragment of a portion of the table shown in FIG. 15 and labeled 21.

The fragmentary showing of wood grain in FIGS. 1-4, 8-11, and 15-18 and shown in detail in FIGS. 5-7, 12-14, and 19-21 is understood to be repeated throughout the surfaces shown. The second and third embodiments are shown with symbolic breaks in length in FIGS. 8-10 and 15, 16, and 18, and those portions of the articles between the break lines form no part of the claimed designs.
